UNITED STATES PATENT OFFICE.

EDWARD ROY HOUSTON, OF BELLEVILLE, ILLINOIS.

CONVERTIBLE LUGGAGE CARRIER.

Application filed March 20, 1924, Serial No. 700,637. Renewed December 31, 1925.

This invention relates to an improved luggage carrier of the type used for attachment to the running board of an automobile, and it has more particular reference to a carrier 5 of this type which is convertible.

It has been my principal aim in devising the present invention to provide a structure which can be utilized in the ordinary manner for carrying luggage on the running 10 board or can be converted to provide a table whenever necessary or desired.

One, and an important feature of the improved device, is the confining wall or member which is imperforate, the same being 15 preferably in the form of a board which, when used as a luggage carrier, is disposed vertically and at right angles to the outer edge of the running board so as to effectively retain small articles in place.

Another feature of the improved invention resides in the provision of novel means 20 for connecting the confining wall or member to the running board, this means being such that it rigidly retains the wall in either of 25 its two positions, the means being also such that it disposes the wall at a point beyond the outer edge of the running board when it is used as a table so as to permit the occupants to seat themselves on the running 30 board with the table in an extended position in front of them.

More specifically speaking, it is my aim to provide an extremely simple and inexpensive convertible carrier of the type under 35 consideration which is merely composed of a board and a plurality of inter-connected links and angle irons, with appropriate fastenings.

Other objects and advantages of the invention will be apparent during the course 40 of the following description.

In the accompanying drawing forming a part of this specification and in which like numerals are employed to designate like 45 parts throughout the same:

Figure 1 is a perspective view of a device constructed in accordance with this invention showing the relative position of parts when the same is used as a table, the same 50 being extended beyond the left-hand running board of an automobile (not shown).

Figure 2 is a section taken approximately 55 on the line 2—2 of Fig. 1, looking in the direction of the arrow.

Figure 3 is a view like Fig. 2, but showing 60 the parts in their normal position when the

device is used as an ordinary luggage carrier.

Figure 4 is a section taken on line 4—4 of 60 Fig. 3.

Figure 5 is a detailed section on line 5—5 of Fig. 2.

Referring to the drawing in detail, it will be observed that the so-called confining wall hereinbefore referred to is in the form of a 65 board 1 of suitable length and thickness. The dimensions of this board will of course vary according to the type of automobile to which the invention is to be applied. Extending across the top of the board at its 70 opposite ends are metallic reinforcing strips 2 which are secured in place by suitable fastenings. Secured to the underside of the board, directly beneath the strips 2, are angle irons 3 which are secured to the board 75 by the same fastenings used to maintain the strips 2 in place. It is to be noted that the vertical flanges of these angle members 3 are disposed substantially flush with the adjacent ends of the board. 80

It has been before intimated that the aforesaid board or confining wall 1 is capable of disposition in either a horizontal position, to provide a table, or in a vertical position to provide an ordinary luggage 85 carrier. While other means may be employed for connecting the board to the running board of the vehicle to permit this result to be attained, I prefer to utilize a series of links and anchoring irons. As seen 90 in the drawing, the anchoring irons are simply short angle irons 4 which are fastened and extend transversely across the running board adjacent the opposite ends thereof. Pivots connected at one end to 95 the inner ends of these irons 4 are comparatively short links 5. At their opposite ends, these links 5 are pivots connected with slightly longer links 6 as indicated at the points 7. It is to be noted that the point of 100 connection just referred to is inward of the lower ends of the links 6 and in this connection it will be observed that the ends last referred to are provided with unoccupied apertures 8 (seen in Figs. 1 and 2) which 105 serve a purpose to be hereinafter described. At their upper ends, the links 6 are pivotally connected to the inner ends of the aforesaid angle bars 3 as indicated at the points 9. These links 6 are further provided between their ends with additional apertures 110 which are adapted to register with simi-

lar apertures formed intermediate the ends of the remaining links 11, these last named links being pivoted at one end to the outer ends of the aforesaid anchoring members 4 and being pivoted at their opposite ends as at 12 to the angle irons 3. In addition to the first named apertures formed in the links 11, they are also provided with adjacent apertures 13 which serve a purpose to be hereinafter described. Through the apertures 10 and the registering apertures in the links 11, small bolts 14 pass, there being thumb nuts 15 threaded on the ends of the bolts as seen to maintain the links in fixed relative relation.

Of course, a plurality of suitable fastenings (not numbered) are employed for securing parts in their appropriate positions. Certain fastenings may be countersunk.

20 In order that the manner of using the invention and its method of application may be more clearly understood, I first direct attention to Fig. 3 wherein the parts are shown in a position to provide the common luggage carrier. In this position, the board 1 is disposed vertically and at right angles to the outer longitudinal edge of the running board B of the automobile. At this time, the links 6 overlie the links 11 and both of these pairs of links are confined against the corresponding angle bars 3. In order to retain the links specified in the relation shown, the bolts 14 are passed through apertures 16 in the angle bars 3 and through the then aligned apertures 13 and 8 of the links 6 and 11. These links are thus rigidly connected with the angle bars 3. Hence, it is obvious that since the links 5 are connected with the links 6 and angle members 4, they serve to tie the board 1 to the running board of the machine. Hence, all parts are held in the position shown in Fig. 3.

Assuming that it is desired to convert the luggage carrier just described into the table shown in Figs. 1 and 2, the bolts 14 and their fastening nuts 15 are simply removed. The lower edge of the board 1 is then grasped and an upward pull exerted thereon which causes it to swing to the horizontal position shown and causes the links 11 and 6 to cross one another. By registering the apertures 10 of the links 6 with the upper apertures of the links 11 and inserting the bolts 14 therethrough and tightening the nuts 15, the board 1 is held in a position to permit it to serve efficiently as a table. When the parts are again returned to the initial position described, the board 1 swings about the pivots 12 and the inner end thereof exerts an upward pull on the links 6 and 5 so as to return the several links to original positions.

The foregoing description when taken in connection with the drawing, will undoubt-

edly serve to enable a clear understanding of the invention to be obtained. Hence, a more specific description is deemed unnecessary.

Although a specific structure embodying a particular arrangement of parts has been set forth, it is to be understood that rearrangement of parts may be made within the scope of the subjoined claims.

I claim:

1. A combined luggage carrier and table comprising a pair of spaced parallel bars adapted to be fastened transversely across the footboard of a vehicle, a board capable of being used as a table when in a horizontal position and as a confining wall of a luggage carrier when in a vertical position, linkage pivoted to said bars and to said board to swing only and substantially in the plane of said bars whereby to support said board in either of the aforesaid positions, and means for fastening adjacent portions of said linkage together in either position of said board.

2. A convertible luggage carrier comprising a confining wall, pairs of links pivotally connected together at their inner ends and pivotally connected at their opposite ends with said board and with the running board of the vehicle respectively, and means in association with said pairs of links for maintaining said wall in either a horizontal or a vertical position.

3. A convertible luggage carrier comprising a confining wall adapted to be disposed in either a horizontal or a vertical position, two pairs of connecting links, there being one pair at each end of said wall and the links of each pair being pivotally connected together and pivotally connected at their opposite ends to said wall and the running board of the vehicle respectively.

4. The structure specified in claim 2, together with additional links pivoted to said wall at points inward of the first named pivotal connection and pivoted at their opposite ends to the running board.

5. A convertible luggage carrier comprising an elongated board, angle irons secured transversely across the board at the opposite ends thereof, pairs of pivotally connected links at the opposite ends of said board, said links being pivotally connected at their outer ends with said board and to the running board of the vehicle respectively, and additional links pivoted to the angle irons inward of the ends thereof and pivotally connected at their opposite ends with the running board of the vehicle, and means for connecting said last named links with one of the links of the aforesaid pairs.

In testimony whereof I have hereunto affixed my signature.

EDWARD ROY HOUSTON.
